F. KLEINSMITH.
AUTOMOBILE DOOR LATCH.
APPLICATION FILED NOV. 24, 1919.

1,348,882.

Patented Aug. 10, 1920.

FIG. 1

FIG. 2

INVENTOR.

Frederick Kleinsmith

BY
Bradford, Morrill & Birney

ATTORNEY.

UNITED STATES PATENT OFFICE.

FREDERICK KLEINSMITH, OF INDIANAPOLIS, INDIANA.

AUTOMOBILE-DOOR LATCH.

1,348,882.

Specification of Letters Patent. Patented Aug. 10, 1920.

Original application filed May 17, 1918, Serial No. 235,121. Divided and this application filed November 24, 1919. Serial No. 340,150.

To all whom it may concern:

Be it known that I, FREDERICK KLEINSMITH, by judicial change of name, formerly ANTHONY F. KLEINSCHMIDT, a citizen of the 5 United States, residing at Indianapolis, in the county of Marion and State of Indiana, have invented certain new and useful Improvements in Automobile-Door Latches, of which the following is a specification.

10 This invention relates to automobile door latches, more especially to a latch capable of operating with a door having an extensible portion. It is very desirable, in extensible automobile doors, that the vertically mov- 15 able portion thereof be of such width as to substantially completely occupy the width of the door. In prior constructions this could not be accomplished due, in a large measure, to the fact that it was necessary for 20 the latch operating means to pass through the body of the door, taking up considerable space therein, which made it impossible to utilize a movable portion which was of a width substantially that of the door itself.

25 By my present invention I obviate such disadvantages, it being among the objects thereof to produce a latch which is simple in construction, reliable in operation, and allows the use of a vertically movable or ex- 30 tensible portion which fills practically the entire width of the door. The present applica- 35 tion is a division of my co-pending applica- tion, Serial No. 235,121, filed May 17, 1918, for extensible automobile doors, allowed June 11, 1919.

In carrying the objects of my invention into effect, I provide a rocking shaft pivoted in the frame of the door below the level of the space occupied by the extensible portion when in lowered position. Suitable operating levers are connected thereto and to the latch forming a U-shaped operating frame so that motion may be transmitted therethrough to move the latch. Preferably these levers are contained within the thickness of the door, only the handles fixed thereto projecting out of the body of the door.

Referring to the accompanying drawings 50 forming a part hereof, and in which similar reference characters denote similar parts,

Figure 1, represents a front view of an automobile door constructed in accordance with this invention some parts being broken 55 away, and

Fig. 2, a section taken along the line indicated on Fig. 1.

The automobile door 1 is provided with a vertically movable member 2 which is usually a frame provided with a glass pane 3; 60 a rack 4 thereon operated by pinion 5 may be used to raise or lower the said movable portion. Screws 6 are provided to expand or contract the movable member, or such screws may be placed in the body of the 65 door to expand the guideways within which the movable member slides, in order to prevent rattling due to looseness of the movable member, as described in my co-pending application above referred to. 70

The door is provided with an ordinary latch 7 which is connected to a handle 8 on the outer side of the door, the handle being operated to release the latch as is usual in constructions of this kind. Connected to 75 the latch 7 is a downwardly extending lever 9, the lower end 10 of which is rigidly secured to a rocking shaft 11 pivoted in the lower portion 12 of the automobile door at a point below the space 13, which is of such 80 depth that when the lowest portion 15 of the movable member 2 is resting upon the top 14 of the member 12 the member 2 is completely inclosed in the door 1. On the opposite side of the rocking shaft 11 is secured 85 a lever 16 at its lower end 17, the upper end of the lever being provided with a handle 18 which projects through a slot 19 formed in the covering 20 of the door. The lever 9 is inclosed by covering 21. 90

The latch 7 is released from the outside of the automobile, as usual, by twisting of the handle 8 which directly operates the latch. When it is desired to release the latch from the inside of the automobile the handle 18 is 95 shifted in its slot, shifting lever 9 through its rigid connection with rocking shaft 11, thus releasing the latch 7. A notch 22 is generally provided in the lower part of the frame 1 to allow same to fit over the rocking 100 shaft 11 and thus allow the movable member to be lowered to practically the bottom of the door.

This construction to outward appearances is exactly the same as the ordinary latch operating means previously commonly used, but my invention contemplates a latch operating device of such a character that it will allow the movable member to occupy 105 practically the entire width of the door, 110

which by the old construction could not be accomplished on account of the latch operating means extending through the door at about the height of the latch and its operating handles.

Having thus fully described my said invention, what I claim as new and desire to secure by Letters Patent, is:

1. In an automobile door, a latch, a latch operating device comprising a member pivoted in the lower portion of said door, and members extending upwardly therefrom on both sides of said door coöperating with said latch for operating the same.
- 10 2. An extensible automobile door having a lower hollow portion, an upper part movable vertically therein, a latch, means for operating said latch extending below the space occupied by the movable part when
- 15 20 the same is lowered and extending upward on opposite sides of the vertical plane of said movable part.
3. An extensible automobile door having a lower hollow body, a vertically movable

member mounted therein and adapted to 25 form a continuation thereof, a latch, a latch operating frame of U-form embracing the space adapted to be occupied by said movable member and extending below said space.

4. An extensible automobile door having 30 a hollow body, a member movable vertically therein and adapted to be extended above said body, a latch, an operating handle for said latch having a rocking shaft located below the space adapted to be occupied by 35 the movable part when in lowered position, a latch connecting lever fixed on said shaft on one side of said space, and an operating lever fixed on said shaft on the opposite side of said space.

In witness whereof I have hereunto set my hand and seal at Indianapolis, Indiana, this 18th day of November, A. D. nineteen hundred and nineteen.

FREDERICK KLEINSMITH. [L. S.]
